(57) **CLAIM**

We claim the ornamental design for a headset, as shown and described.

DESCRIPTION

FIG. 1 is a front right perspective view of a headset;
FIG. 2 is rear right perspective view thereof;
FIG. 3 is a rear left perspective view thereof;
FIG. 4 is a front view thereof;
FIG. 5 is a rear view thereof;
FIG. 6 is a left view thereof;
FIG. 7 is a right view thereof;
FIG. 8 is a top view thereof; and,
FIG. 9 is a bottom view thereof.

The broken lines in the drawings are for illustrative purposes only and form no part of the claimed design.
